 3 Claims. (Cl. 85—79)

ABSTRACT OF THE DISCLOSURE

An anchor rod, such as a mine roof bolt or rock anchor, having two earth engaging members relatively laterally displaceable toward the wall of the hole into which the rod is received and in which it is to be locked upon relative displacement of the members in the axis of the hole.

This invention relates to anchor rods.

More particularly, the invention relates to an anchor rod having two earth-engaging members operable by moving the members relatively toward one another in the axis of the hole into which the anchor rod is received and in which it is to be locked. Such a rod is also known as a mine roof bolt or rock anchor. In the anchor rods of this invention a U-shaped member is fixed to one of said earth engaging members, the legs of the U-shaped member being slidably received in grooves in the other of said earth engaging members.

The object of the invention, generally, is to provide an improved anchor rod of the kind having two earth-engaging members.

A specific object of the invention is to provide an anchor rod having two earth-engaging members relatively laterally displaceable toward the wall of the hole into which the rod is received and in which it is to be locked, upon the relative displacement of the members in the axis of the hole.

Another specific object of the invention is to provide such a device so made that all of the component parts are assembled as a unit, ready to be used.

Other advantages of the invention may be gleaned from reading the specification to follow.

In the drawing, wherein like numerals of reference indicate corresponding parts in the various figures,

FIGURE 1 is a side elevation of the device in its initial, unloaded position;

FIGURE 2 is a longitudinal sectional view of the device introduced into a hole and held in such position, preparatory to operating the device fully to operate the jaws to their intended, operative locked position in the hole, the rod of the device being shown in elevation;

FIGURE 3 is an elevation of the device, now in operated (expanded) locked position in the hole;

FIGURE 4 is a section on line 4—4 in FIGURE 2; and

FIGURE 5 is a section on line 5—5 in FIGURE 2.

As is known, an anchor rod is inserted into a prepared hole, shown as H, drilled into rock or the like from the surface.

As already stated, two members or elements adapted to be relatively displaced both longitudinally and laterally are provided as means for locking the anchoring device in the hole H. Such members are shown as 10 and 11.

The member 10 is formed with an axial threaded bore in which is threadingly received the threaded shank portion 14 of the anchor bolt 12. The anchor bolt 12 is rotated on its axis by a head 13. The bore of the member 10 is enlarged as at 19. One side of the member 10 is cut off along a plane disposed at an acute angle to the longitudinal axis of the bolt, thus presenting inclined or bevelled edges 15.

2

The diameter of the member 10 is such as to just be freely received into the hole H.

The complementary member 11, formed with a circular recess or bore 32, presents two slanted edges 16 which are adapted to engage and co-operate with the inclined edges 15 of the companion member 10. In effect the two members 10 and 11 constitute co-operating wedges.

Fixed to the wedge member 11, adjacent its apex as at W (see FIGURE 2) is one leg 17 of a U-shaped device shown as 18, the other leg 24 of which is directed substantially parallel to the leg 17. The legs 24 and 17 of the device 18 are received, and are slidable in rectangular grooves 22 made into the wall of the member 10.

As will be seen, the device assumes essentially three positions, such positions being a function of the relative longitudinal position of the member 11 and the companion member 10. Thus, as seen in FIGURE 1, the initial and neutral position of the member 11 is such that the device is unexpanded. The member 11 is in effect suspended from the member 10.

When the device is to be used it is first pre-loaded, this is, the bolt 12 may be turned slightly in the member 10, say, by means of one's two hands, to engage at its upper end and the horizontal leg 20 of the device 18 and to raise the wedge member 11 relatively to the member 10. The member 11, its edges 16 riding on the edges 15 of the member 10, will thus move laterally. As the member 11 rides on the member 10 and moves laterally, the U-shaped device 18, more particularly its leg 17, bends or flexes outwardly from top to bottom so that, in effect, the wedge member 11 is displaced laterally more at the lower end than at its upper end (as best seen in FIGURE 2). The device may now be said to be preloaded, in that when inserted into the hole (as seen in FIGURE 2), the device is held in such position by the friction between the members 10 and 11 and the wall of the hole, such friction being a function of the pressure of the members against the wall.

Alternatively, preloading may be effected by (manually) spreading the lower extremities of the members 10 and 11 apart permanently, to deform the leg 17 slightly, so that the effective diameter of the complementary members 10 and 11 is larger than the hole. Such manual preloading may be effected at the site.

As will be clearly seen, the device is supplied fully assembled, ready to be used, all of the component parts being held together as a unit. The rod is held to the member 10, and the members 10 and 11 are held one to the other by the U-shaped member 18 which in turn is permanently attached to the member 11 but removably attached to the member 10.

The bolt 12 is next pulled downwardly (lowered) as by turning a nut 40 threaded on the rod against a plate 41 pressed against the formation. The wedge member 10 will now lower in the hole, sliding on the wedge member 11, to its ultimate position, that is, the expanded position of the device, as best seen in FIGURE 3.

I claim:

1. In an anchor rod to be inserted into a cylindrical hole drilled into a first formation, the combination of a rod, a formation-engaging wedge member through which said rod is threaded, a second formation-engaging wedge member, said two members subtending a transverse periphery of substantially 360°, cam means on said members whereby said members may be relatively displaced laterally to engage the formation as said members are moved one toward the other axially of said rod, and a guide movable on said first member in a direction parallel

with the axis of said rod, said guide member being substantially U-shaped and including two legs, one of said legs being attached to the upper end of said second member and the other of said legs being free and slidible in a longitudinal groove formed in the wall of said first wedge member.

2. An anchor rod as in claim 1, wherein the legs of said U-shaped guide normally converge slightly towards their ends whereby said guide tends to retain said wedge means in assembled relationship for convenient handling.

3. An anchor rod as in claim 1, including a nut threaded on said rod and a formation-engaging plate suspended by said nut and movable lengthwise of said rod.
